DRIVE-IN CANOPY

Harold Baker, Lexington, Ky., assignor to Baker Steel
and Engineering Corporation, Lexington, Ky., a corpo-
ration of Kentucky

Filed Aug. 2, 1961, Ser. No. 66,171

Term of patent 14 years

(Cl. D13—1)

Fig. 1.

FIG. 2.

FIG. 3.

Fig. 4.

FIG. 5.

FIG. 6.

FIGURE 1 is a perspective view of a drive-in canopy, showing my new design.

FIGURE 2 is a side elevational view thereof.

FIGURE 3 is a fragmentary cross sectional view taken on the line 3—3 of FIGURE 2.

FIGURE 4 is a perspective view of a drive-in canopy showing a modified form of the design shown in FIGURES 1-3, the right edge shown fragmentarily for convenience of illustration only.

FIGURE 5 is a fragmentary side elevational view of the form of the design shown in FIGURE 4.

FIGURE 6 is a fragmentary cross sectional view taken on the line 6—6, FIGURE 5.

The dominant features of my design reside in the portions shown in full lines, such full line portions being

characterized by the twisted configuration of the roof proper as best shown in the drawings. This is a continuation-in-part of my copending application, Serial No. 64,331, now abandoned.

I claim:

The ornamental design for a drive-in canopy, substantially as shown and described.
